UNITED STATES PATENT OFFICE.

EDELMIRA DE S. MORRISON, OF DENVER, COLORADO.

DESIGN FOR A PILLOW-TOP.

SPECIFICATION forming part of Design No. 36,162, dated December 9, 1902.

Application filed March 18, 1902. Serial No. 98,843. Term of patent 8½ years.

To all whom it may concern:

Be it known that I, EDELMIRA DE S. MORRISON, a citizen of the United States of America, residing at Denver, in the county of Arapahoe and State of Colorado, have invented a new, original, and ornamental Design for Pillow-Tops, of which the following is a specification, reference being had to the accompanying drawing, forming part thereof.

10 The figure is a plan view of a pillow-top, showing my invention.

As shown in the drawing, the ornamental design is an article of manufacture, and consists of a pillow-top having the particular 15 ornamentation made the subject of illustration, which is a unitary design and consists of a field A, in the center of which there are ornamental letters arranged into the words shown in the illustration, which are surrounded by curved lines B in the form of scrolls C, 20 that radiate from said words to the border edges of the pillow-top, thus leaving the said ornamental words in the central portion D of the pillow-top.

The leading feature of my design consists 25 of ornamental letters arranged into the words "Here's to a jolly good fellow," arranged to form the center of a field of ornamental scrollwork that is arranged to coöperatively unite with the ornamental letters, so as to 30 give to the entire design of the pillow-top a highly ornamental and unitary effect. The curved lines B, which form the scrolls C, are arranged in conventional groups in harmonious order relative to each other in the field 35 surrounding said letters.

Having thus fully described my invention, I claim as new and desire to secure by Letters Patent—

The ornamental design for a pillow-top substantially as shown and described.

In testimony whereof I have signed my name to this specification in the presence of two subscribing witnesses.

EDELMIRA DE S. MORRISON.
